UNITED STATES PATENT OFFICE.

JOSEPH HERMAN, OF NEW YORK, N. Y., ASSIGNOR TO AMERICAN TELEPHONE AND TELEGRAPH COMPANY, A CORPORATION OF NEW YORK.

MONITORING SET FOR TELEGRAPH REPEATERS.

Application filed June 27, 1923. Serial No. 648,096.

To all whom it may concern:

Be it known that I, JOSEPH HERMAN, residing at New York, in the county of New York and State of New York, have invented 5 certain Improvements in Monitoring Sets for Telegraph Repeaters, of which the following is a specification.

This invention relates to arrangements for monitoring on telegraph lines and more 10 particularly for monitoring on such lines where through repeaters, having no provision for monitoring, are utilized.

The monitoring arrangements of the invention may be used to considerable advantage 15 for observing the transmission through the repeater set and for locating faults in a line into which a number of through repeaters are connected. The arrangements of the invention furthermore provide means for 20 sending and receiving at a point where a repeater of this type is employed.

One of the main operating features of the arrangements of the invention consists in 25 utilizing the relay windings in the artificial line circuit of the repeater for operating the relay so as to make the relay serve as a sending pole-changer under control of the monitoring set. Other features and advantages 30 of the arrangements of the invention will appear more fully from the detailed description hereinafter given.

In the following description the monitoring arrangements of the invention will be disclosed in the manner in which they may be applied to so-called metallic polar-duplex 35 telegraph repeaters. It should be understood, however, that this is only a particular application of the invention and that the invention may be used in connection with 40 other types of telegraph systems. The invention may be more fully understood from the following description together with the accompanying drawing in the Figures 1, 2, 3, 4, 5 and 6 of which are illustrated circuit 45 diagrams embodying the arrangements of the invention. Fig. 1 shows in detail the circuit arrangement of a metallic polar-duplex telegraph repeater set and the monitoring set of the invention. Figs. 2, 3, 4, 5 and 6 are schematic diagrams illustrating 50 the polarity of the telegraph currents encountered under various conditions.

In Fig. 1 is shown a west line LW and an east line LE interconnected by a through 55 telegraph set. Line LW is balanced by the

network NW and line LE is balanced by the network NE. The line LW includes a relay having the line windings 1 and the network windings 2 interconnected by the contacts of jack JW, points e and i being connected together and points f and j being connected together. These relay windings normally control the pole changer apparatus TW to repeat signals from line LW to line LE. The mid-points g and h of the windings 1 and 2 are connected to the pole changing apparatus TE. Associated with the pole changers TW and TE are the noise killer devices 5 and 6. The line LE includes a relay having the line windings 3 and the network 65 windings 4 interconnected through the contacts of jack JE, points i' and e' being connected together and points j' and f' being connected together. The mid-points g' and h' of windings 3 and 4 are connected to the pole changer TW. The signals coming in 70 over line LW operate the relay included therein which operates the pole changer TW to repeat the signals out over line LE. The signals coming in over line LE operate the 75 relay included therein which operates the pole changer TE to repeat the signals out over line LW in a well known manner.

The monitoring set of the invention includes the plug P which may be associated with the jacks JW or JE. Two of the sets of conductors of plug P are associated with the contacts of a two position switch S. A relay 7 is provided controlled by a key K. The relay 7 has two armatures which operate between the fixed contacts a, a, and b, b. One of the sets of conductors of plug P are connected to these armatures. A sounder 10 is provided connected to one set of conductors of plug P and a battery 9 is provided 80 which may be associated with contacts a, a, and b, b, over the contacts of switch S.

When plug P is inserted in jack JW, with key K closed, and the switch S is on its normal position the line windings 1 will be 85 connected to the network windings 2 and service may take place between LW and LE in the normal manner. Points e and f will be connected with points i and j over the 90 following circuit; over contacts of jack JW and plug P, conductors 11, contact of switch S, conductors 14, contacts of switch S, conductors 15, contacts a, a and over conductors 13 to points i and j. The pole changer TE 95 is connected to points g and h which are 100 105 110

connected over conductors 12 and the contacts of switch S to the last mentioned circuit and accordingly service may take place between line LE and line LW in the normal manner. The sounder 10 is bridged across the contacts of switch S included in the above circuits and accordingly the transmission from LE to LW may be observed.

When both the east line and west line subscribers have their keys closed the current in the line will be zero as the battery potentials at the ends of the line oppose each other. Such a condition is illustrated schematically in Fig. 2, the condition of no current being indicated by showing the line and line windings as dotted lines. It will be seen however that current from the local batteries will flow through the network windings as indicated by the arrows and will tend to hold the armature of the pole changer in one direction. If the monitoring operator now desires to send to the east line LE the key K will be opened. This will operate relay 7 which will cause its armatures to move over to the contacts b, b. The contacts are connected over conductors 16, contacts of switch S, and conductors 17 to the battery 9 and have a polarity normally opposite to contacts a, a. Accordingly the operation of key K and relay 7 will reverse the polarity of the current supplied over conductors 13 to the network windings 2 and cause the armature of the sender TW to change its position thereby transmitting signals over line LE. Such a condition is shown schematically in Fig. 5, the heavy arrows showing the direction of the normal current and the dotted arrows showing the direction of the current to be reversed upon the operation of key K. It will be noted that the operation of key K will have no effect on the line, such as LW, and accordingly will not effect the west subscriber under these conditions.

If the east subscriber opens his key to break the sender the local transmitter TE will reverse the polarity of the contacts a, a, and they will now be of the same polarity as contacts b, b. Accordingly, any operation of key K and relay 7 will only serve to send current through the network windings in one direction and will not operate the transmitter TW. Such a condition is illustrated in Fig. 6, it being pointed out that under these conditions the dotted arrows and heavy arrows which indicate the current in the network windings will for both operations of the key K be in the same direction. The condition of the line when the east subscriber opens his key is illustrated schematically in Fig. 4.

When the monitoring set is connected with jack JW the west subscriber hears only the message coming from the east line and does not hear the monitoring operator.

However, the west subscriber may interrupt both the east subscriber and the monitoring station by opening his key. The condition of the line currents when the west subscriber opens his key is shown schematically in Fig. 70 3. Such interruption can be remedied by throwing the switch S to the left or off position. This will remove the network windings 2 from the line windings 1 and connect the network windings to conductors 75 17 and the metallic battery 9 over the contacts of switch S during the marking or closed position of the monitoring key K. There is therefore no danger of the west relay operating when the east subscriber sends even though the west line balance has been destroyed. This is true because the artificial line windings 2 will be disconnected from the line windings 1 and connected to the battery 9 of fixed polarity 85 while receiving signals.

To send from the monitoring station out over the west line LW, the plug P would be connected to jack JE. The operation would then be substantially similar to that 90 already given.

While the invention has been disclosed in certain specific arrangements which are deemed desirable, it is understood that it is capable of embodiment in many and widely varied forms as defined by the appended 95 claims.

What is claimed is:

1. A transmission line including two line sections interconnected by a telegraph repeater, said telegraph repeater including line windings and balancing network windings in each line section, pole changers connected to the midpoints of said windings, the pole changers connected to the midpoints of the windings in one line section being controlled by the windings in the other line section, and switching means connected to each set of said windings and their midpoints, and monitoring apparatus including switching means adapted to be connected to either of said last mentioned switching means, and means associated with said switching means for reversing the polarity of the current normally applied to the network windings 110 of the set.

2. A transmission line including two line sections interconnected by a telegraph repeater, said telegraph repeater including line windings and balancing network windings in each line section, pole changers connected to the midpoints of said windings, the pole changers connected to the midpoints of the windings in one line section being controlled by the windings in the other line section, 125 and switching means connected to each set of said windings and their midpoints, and monitoring apparatus including switching means adapted to be connected to either of said last mentioned switching means, and 130

means associated with said switching means for reversing the polarity of the current normally applied to the network windings of the set without disturbing the electrical condition of the line windings of the set.

3. A transmission line including two line sections interconnected by a telegraph repeater, said telegraph repeater including a set of line windings and network windings in each line section, pole changers connected to the midpoints of said windings, the pole changer connected to the midpoints of the windings in one line section being controlled by the windings in the other line section, and switching means connected to each set of said windings and their midpoints, and monitoring apparatus including switching means adapted to be connected to either of said last mentioned switching means, circuit arrangements connected with said switching means whereby the line windings and network windings may be connected together and the pole changer may be connected to their midpoints at points in said circuit arrangements in said monitoring apparatus, and receiving apparatus connected to said last mentioned points.
4. A transmission line including two line sections interconnected by a telegraph repeater, said telegraph repeater including a set of line windings and network windings in each line section, pole changers connected to the midpoints of said windings, the pole changer connected to the midpoints of the windings in one line section being controlled by the windings in the other line section, and switching means connected to each set of said windings and their midpoints, and monitoring apparatus including switching means adapted to be connected to either of said last mentioned switching means, circuit arrangements connected with said switching means whereby the line windings and network windings may be connected together and the pole changer may be connected to their midpoints at points in said circuit arrangements in said monitoring apparatus, and a two position switch associated with said circuit arrangements in said monitoring apparatus whereby said network windings may be disconnected from said line windings and may be connected to a battery of fixed polarity.
- 45 means adapted to be connected to either of said last mentioned switching means, circuit arrangements connected with said switching means whereby the line windings and network windings may be connected together and the pole changer may be connected to their midpoints at points in said circuit arrangements in said monitoring apparatus, and means connected to said circuit arrangements for reversing the polarity

of the current normally applied to the network windings.

5. A transmission line including two line sections interconnected by a telegraph repeater, said telegraph repeater including a set of line windings and network windings in each line section, pole changers connected to the midpoints of said windings, the pole changer connected to the midpoints of the windings in one line section being controlled by the windings in the other line section, and means connected to the network windings of at least one of said line sections for reversing the polarity of the current normally applied to said network windings and for simultaneously maintaining the normal electrical condition of the line windings of the set.

6. A transmission line including two line sections interconnected by a telegraph repeater, said telegraph repeater including a set of line windings and network windings in each line section, pole changers connected to the midpoints of said windings, the pole changer connected to the midpoints of the windings in one line section being controlled by the windings in the other line section, and switching means connected to each set of said windings and their midpoints, and monitoring apparatus including switching means adapted to be connected to either of said last mentioned switching means, circuit arrangements connected with said switching means whereby the line windings and network windings may be connected together and the pole changer may be connected to their midpoints at points in said circuit arrangements in said monitoring apparatus, and a two position switch associated with said circuit arrangements in said monitoring apparatus whereby said network windings may be disconnected from said line windings and may be connected to a battery of fixed polarity.

In testimony whereof, I have signed my name to this specification this 26th day of June, 1923.

JOSEPH HERMAN.
